UNITED STATES PATENT OFFICE

WILLIAM E. KIDDER, OF KALAMAZOO, MICHIGAN, ASSIGNOR TO KALAMAZOO SLED COMPANY, OF KALAMAZOO, MICHIGAN

SLED

Application filed June 23, 1930. Serial No. 462,998.

The main objects of this invention are:

First, to provide an improved sled of the steering or coaster type in which the runners may be deflected or curved substantially throughout the length thereof thereby greatly increasing the steering action.

Second, to provide a steering or coaster sled in which the portion of the runners carrying the load are curved or deflected to secure the steering action which enables the sled to be effectively steered on hard surfaces such as ice.

Third, to provide a structure embodying these advantages which is very easily manipulated or steered.

Objects pertaining to details and economies of my invention will definitely appear from the description to follow. The invention is defined in the claims.

20 A structure which embodies the features of my invention is clearly illustrated in the accompanying drawings, in which:

Fig. 1 is a side elevation of my improved steering sled.

25 Fig. 2 is an inverted view with the runners in straight or normal position.

Fig. 3 is an inverted view with the runners deflected.

Fig. 4 is an enlarged fragmentary section 30 on line 4—4 of Fig. 2.

Fig. 5 is an enlarged fragmentary section on line 5—5 of Fig. 2.

Fig. 6 is an enlarged fragmentary section on line 6—6 of Fig. 2.

35 Fig. 7 is an enlarged fragmentary section on line 7—7 of Fig. 2.

Referring to the drawings, the runners 1 of T cross section are bent upwardly at their front ends and connected by a cross bar 2, the 40 connection being by pivots 3.

The knees 4 are provided with downwardly diverging legs 5 and are preferably sheet metal stampings. The knees have inwardly projecting bracket portions 6 forming seats 45 for the benches 7. The raves 8 are mounted on the outer ends of the benches. The benches and knees are connected by the rivets 9 which also engage outer transverse slots 10 formed in the knees.

50 The knees also have inner transverse slots

11 which are engaged by the headed studs 12. This permits a pivotal and sliding movement of the knees relative to the benches, the pivotal action alternating on the rivets and the studs and depending on the direction in which the runners are flexed, as will be clear from an inspection of Fig. 3.

The links 13 are pivotally engaged with the rivets 9 connecting the front bench to the raves and to the front ends of the runners 60 by the pivots 3.

The steering lever 14 is pivotally connected to the cross bar 2 at 15 and has a longitudinal slot 16 engaging the pivot 17 on the forward end of the centerboard 18 of the top. This 65 top board is secured to the front and rear benches by means of the fastenings 19. The top boards 20 disposed at each side of the board 18 are similarly fastened.

The steering bar 21 is fixedly secured to the 70 starting lever so that when swung on its pivot the steering lever fulcrumming on the pivot 17 deflects the forward ends of the runners as illustrated, for example, in Fig. 3. A cross bar 22 is secured to the raves by the 75 rivets 23.

With this arrangement of parts the runners may be flexed or curved substantially uniformly throughout their length, thus allowing that portion of them sustaining the 80 load to curve and more effectively steer the sled. The runners are easily flexed and the sled turned in a shorter radius than is otherwise possible, owing to the greater curvature and the more effective engagement of the 85 runners with the surface.

I have illustrated and described my improvements in an embodiment which I have found highly satisfactory. I have not attempted to illustrate and describe other embodiments or adaptations which I contemplate as it is believed this disclosure will enable those skilled in the art to embody or adapt my improvements as may be desired.

Having thus described my invention what 95 I claim as new and desire to secure by Letters Patent is:

1. The combination of flexible runners, pairs of front and rear knees secured to said runners and each having longitudinally 100

- spaced inner and outer transverse slots therein, benches arranged on said knees, raves disposed on the outer ends of said benches, said benches and raves being connected by bolts arranged through and securing the outer slots of said knees, headed studs on said benches engaging the inner slots of said knees, a top secured to said benches, a cross bar connecting the front ends of said runners, links pivotally connected to the end of said cross bar and to the front bench, and a steering lever pivotally mounted on said cross bar and having a pin and slot connection to the front end of said top.
15. 2. The combination of flexible runners, pairs of front and rear knees secured to said runners and each having longitudinally spaced inner and outer transverse slots therein, benches arranged on said knees, raves disposed on the outer ends of said benches, said benches and raves being connected by bolts arranged through and engaging the outer slots of said knees, headed studs on said benches engaging the inner slots of said knees, a top secured to said benches, a cross bar connecting the front ends of said runners, and a steering lever pivotally connected to said top and cross bar.
3. The combination with a top, of flexible runners, pairs of knees secured to said runners and each having longitudinally spaced inner and outer transverse slots therein, pivots engaging said slots whereby said knees are connected to said top for pivotal and limited sliding movement on said pivots, a cross bar connecting the front ends of said runners, a steering lever pivotally mounted on said cross bar and having pin and slot connection to the front end of said top, and a steering bar on said lever.
4. The combination with a top, of flexible runners, pairs of knees secured to said runners and each having longitudinally spaced inner and outer transverse slots therein, pivots engaging said slots whereby said knees are connected to said top for pivotal and limited sliding movement on said pivots, and a steering lever fulcrumed on said top and operatively connected to the forward ends of said runners.

In witness whereof I have hereunto set my hand.

WILLIAM E. KIDDER.
